UNITED STATES PATENT OFFICE.

GEORGE W. SHIEBLER, OF BROOKLYN, NEW YORK.

DESIGN FOR A SPOON OR FORK.

SPECIFICATION forming part of Design No. 12,399, dated August 2, 1881.
Application filed June 15, 1881. Term of patent 7 years.

To all whom it may concern:

Be it known that I, GEORGE W. SHIEBLER, of Brooklyn, in the county of Kings and State of New York, have invented a new and ornamental Design for Spoons and Forks; and I do hereby declare that the following is a description of the same.

The design is represented in the accompanying photograph of the spoon.

10 The outline of the handle is elliptical at the end, and the edges are tapering. There is a central medallion ornament, *a*, with a row of beads around it. The edges of the handle are ornamented with beads *c* and *d*, that are wider apart toward the end than they are at the shank or narrowest part of the handle, and there are leaflet ornaments between the two beads, as at *e*, to form the ornamental border. The leaflet ornaments at *f* branch inwardly 15 from the outer bead, *d*, and surround the quarterfoil ornament *g*. The tortuous stems and leaves at *h* and *k* form ornaments to the mid-

dle portions of the surface of the handle. At the end of the handle the surface is ornamented with scrolls and leaflets at *i*. On the handle, near the junction with the bowl or prongs, there are the scroll and leaflet ornaments *l*.

I claim as my invention—

1. The design of the shape and configuration of the beads and leaflet ornaments *c d e*, forming the border, as represented.

2. The design of the medallion *a*, with a beaded border, as represented.

3. The design of the tortuous stems and leaflets *h k*, as represented.

4. The design of the scroll and leaflet ornaments *i* and *l*, at the border of the ornaments, as represented.

Signed by me this 13th day of June, A. D. 1881.

GEO. W. SHIEBLER.
